ATTORNEY.

UNITED STATES PATENT OFFICE

FRANK FISHER, OF NEW YORK, N. Y.

CHRISTMAS-TREE-ORNAMENT FASTENER

Application filed March 20, 1929. Serial No. 348,394.

This invention relates to fasteners and particularly to Christmas tree ornament and light attachment means, one of the objects of my invention being the provision of a device 5 which is adapted to be conveniently secured to a branch of a Christmas tree and which may be employed to support and suitably position several ornaments or lights.

Another object of my invention is the 10 provision of adjustably fastening means which may be manipulated for suitably disposing the ornament or light attached thereto in a desired position.

Other objects and advantages will appear 15 hereinafter, the novel features and combinations being set forth in the appended claims.

Fig. 1 is a plan view of a fastening device embodied in my invention.

20 Fig. 2 is a plan view of another development of my invention.

Fig. 3 is a detail view of an element of the fastening device illustrated in Fig. 2.

25 Fig. 4 is a detail view of another element of my invention.

Figs. 5 and 6 are perspective views of a further development of my invention.

Fig. 7 is a vertical sectional view of a modified form of my invention taken on the 30 line 7—7 of Fig. 8.

Fig. 8 is a top view of Fig. 7.

Fig. 9 is a perspective view of a still further modification of my invention.

Referring particularly to Fig. 1 of the 35 drawing, the numeral 10 designates an upper hook member of a fastening device preferable comprising an integral piece of resilient

spring wire. The upper hook 10 is disposed at one extremity of a body portion 11 which 40 is substantially straight and is provided at

its lower extremity with a looped element 12 adapted to be disposed around the periphery of an electric light socket or base of a bulb and to resiliently grip the same. The 45 upper loop or hook 10 is adapted to be disposed over a branch of a Christmas tree for retaining a light socket and bulb suspended therefrom.

It should be understood that the device as 50 a whole is substantially J-shaped and that

each of the hooks are by reason of the resiliency of the material, adapted to grip an object disposed therein. An ornament may be attached to the lower loop 12 if desired.

In Figs. 2, 3 and 4 of the drawings my 55 improved fastening means is shown to comprise separate detachable hook elements 20 and 21 each comprising a rectangular plate 22 and 23, respectively. Each plate is secured to the base of one of the hook elements and the plate 22 as illustrated in Fig. 3 is provided with tapered dovetail grooves 24 and 25. The plate 23 is provided with a tapered dovetail extension 26 adapted to be disposed in either of the grooves 24 and 25 60 for detachably attaching the hook elements 20 and 21 together. It should be understood that the relation of the hook element 20 to the hook element 21 may be varied as desired with this form of my invention. 65

In the modified form of my invention illustrated in Figs. 5 and 6, the hook elements 20' and 21' are provided at their extremities with cubical base members 27 and 28, respectively. 70

The base member 27 is provided on its lower and side surfaces with tapered dovetailed grooves 29, 30 and 31 and the base member 28 is provided with a tapered extension 32, adapted to be selectively disposed in any one of the grooves 29, 30 and 31 for attaching the hook elements 20' and 21' together in a suitable relation. It should be understood that the hook element 20' which may be employed for suspending the device from a branch of a tree, may be so positioned relative to the hook element 21' which is adapted to resiliently grip an electric light socket, as to dispose the two hook elements at right angles to each other or in line with each other as desired. 80

In the modified form of my invention illustrated in Figs. 7 and 8, the hook elements 20^a and 21^a are provided with disc shaped base members 33 and 34, respectively. The adjacent surface of the discs 33 and 34 are provided with inter-engaging teeth 35 and 36. A spring clip member 37 comprising radially disposed arms 38 is mounted on top of the disc 33 and is provided with resilient integral extensions 39 which are disposed around the 95

edges of the superimposed discs and engaged against the lower surfaces of the disc 34 for urging the disc together. It should be understood that the two discs are held together by the resilient clip member 37 and that they are restrained from relative rotation by the inter-engaged teeth 35 and 36. It should be further understood that when it is desired to adjustably position one hook member relative to the other the discs may be pulled apart for disengaging the teeth thereof and when the teeth are disengaged the discs may be rotated relative to each other and reset in a desired position by permitting the spring clip 37 to urge the discs together for interlocking the teeth 35 and 36.

In the modified form of my invention illustrated in Fig. 9, the body portion 40 is of substantially circular shape and is integral with the loop element 41.

Having thus fully shown and described an embodiment of my invention, what is desired to be secured by Letters Patent of the United States is:—

25 1. A fastening device for Christmas tree ornaments comprising a resilient hook adapted to be engaged on a branch of a Christmas tree, a member attached to said hook and having tapered dovetailed grooves, a second 30 member having a tapered dovetailed extension adapted to be selectively engaged in the grooves of said first mentioned member and a hook member attached to said second mentioned member adapted to support an electric 35 light socket.

2. A fastening device of the class described, comprising a member having tapered dovetailed grooves in a surface thereof, a second member having a tapered dovetailed extension, and hook members attached to each of said members, the extension of said second mentioned member being adapted to be inserted in any desired groove of said first mentioned member for suitably positioning the hook of said second member relative to the hook of said first mentioned member.

In testimony whereof I have affixed my signature.

FRANK FISHER.
